COMBINED ILLUMINATING AND COOKING
MEANS

Elsie C. Christ, Westbury, N. Y.

Application March 10, 1938, Serial No. 195,030

4 Claims. (Cl. 219—37)

This invention relates to a combined electric lamp and utility heater, wherein the heater may be used for the preparation of hot refreshments while entertaining guests in the living room without interruption, or for preparing meals by a bedridden person, while the lamp is used to illuminate the living room or bedroom.

It is an object of the invention to provide a lamp stand or pedestal with an electric heating element which will not detract from the artistic appearance of the lamp pedestal.

It is another object of the invention to provide a heater combined with a lamp which will not materially increase the cost of manufacture of the lamp.

It is a further object of the invention to provide a combined lamp and heater wherein the heater may be converted into an article support without interfering with the utility of the heater.

It is a still further object of the invention to provide the heater of a combination lamp and heater with a conveniently located switch whereby a person may connect or disconnect the heater with an electric circuit without arising from a chair located adjacent the combination lamp and heater.

A still further object of the invention is to mount a heater on a lamp pedestal without over-balancing the lamp pedestal.

30 In the drawing accompanying and forming a part of this application,

Figure 1 is an elevational view of a "bridge lamp" having combined therewith a utility heater.

35 Figure 2 is a fragmentary view, on an enlarged scale, and partly in section to show the mounting of the utility heater on the pedestal of the lamp, electrical connection of an electric heating element to a source of supply, and means to convert the heater into an article support.

40 Figure 3 is a plan view of the electric heating element of the heater; and

Figure 4 is a perspective view of a cover constituting the means for converting the heater into an article support, the cover being partly broken away to show the structure of the same.

In illustrating the embodiment of the invention in the accompanying drawing, there is shown a floor lamp of the type known commercially as a "bridge lamp" comprising a pedestal 5 of tubular material having a supporting base consisting of a plurality of foot members 6 of scroll formation connected to one end of the pedestal.

55 An electric lamp socket 7 arranged with a pull

chain actuated switch, as indicated at 8, and having a lamp shade 9, is supported on the end portion of the pedestal opposite the base 6 by a hollow arm bracket 10 having at one end a pair of parallelly extending members rotatably mounted on the pedestal, as at 11, and the opposite end adapted to support the socket 7 by a tubular member fixed at the opposite ends in the socket and bracket, as shown at 12 in Figure 1. The lamp socket is electrically connected to a 10 source of electricity by an electric conductor 13 having a blade contact terminal plug 14 at one end and engaged and extended into the bores of the pedestal 5, the bracket 10 and the supporting member 12 with the opposite end of the conductor connected to the terminals of the socket.

To provide the pedestal with an electric heater without detracting from the appearance of the lamp pedestal or interfering with the distribution of the weight of the lamp pedestal whereby 20 it will not become top heavy, a portion of the pedestal intermediate the lamp bracket 10 and the base 6 and usually near the base, is offset or bent laterally of the longitudinal axis of the pedestal to U form, as at 15 in Figure 1.

The heater comprises a dish shaped casing member 16, in the present instance of semi-spherical shape, but which may be of suitable angular form corresponding to the design of the lamp and pedestal. The lower or closed portion 30 of the member 16 is arranged with an opening 17 centrally thereof and connected to a tubular portion 18 having at one end an exterior shoulder 19 to engage the outer surface of the lower portion of the member 16 and facilitate the connection between the member 16 and the tubular portion 18, as by soldering or welding. The bore of the tubular portion 18 and opening 17 are in alignment with each other. The opposite end of the tubular portion 18 is cut at an angle corresponding to the angle of the juncture between the portion of the pedestal 5 adjacent the base 6 and U portion 15, as clearly shown at 20 in Figure 2, whereby the tubular portion 18 is mounted on the pedestal and permanently attached thereto by soldering or welding. The wall of the pedestal 5 engaged by the tubular portion 18 is arranged with an opening 21 in alignment with the bores of tubular member 18 and the pedestal portion 5 adjacent the base 6, to permit the passage of an 50 electric conductor 22 connected to the conductor 13 and having terminal portions extended into the casing member 16. One wire of the conductor 22 is connected to a terminal of switch mechanism indicated in a general way at 23 and 55

40

55

mounted in the member 16 relative to an opening in the wall thereof for the passage of an actuating lever of the switch mechanism, as shown at 24 in Figure 2. The other wire of the 5 conductor 22 is connected to a contact of a pair of contacts in the form of pins 25 mounted on and insulated from a leg portion of an angle bracket 26 having the other leg portion thereof mounted on the wall of the member 16. The 10 other contact pin 25 is connected by a wire 27 to the terminal of the switch mechanism 23 opposite to the terminal thereof connected to conductor 22. The bracket 26 is mounted in the member 16 to position the contact pins 25 in a 15 vertical plane adjacent to a horizontal shoulder extending around the open end and below the edge of the member 16, as at 28.

The heating element of the heater comprises a disk or plate 29 of heat refractory and electric insulating material and of a diameter to engage the shoulder 28 of the member 16. The upper face of the plate 29 is arranged with a continuous sinuous groove having the ends thereof terminating adjacent and in parallel relation to 25 each other, as shown at 30 in Figure 3. An electric resistance coil 31 is engaged in the groove 30 with the opposite ends of the coil connected to tubular or socket contact members 32 fixed in the plate at the ends of the groove 30 and 30 having the socket portions projecting from the face of the plate opposite the grooved face to engage and make contact with the contact pins 25 mounted in the member 16 when the plate 29 is engaged on the shoulder 28, as shown in Figure 35. 2. By the arrangement of the releasably electrical connection between the heater coil 31 and the contacts 25, it is possible to remove the heater plate 29 from the supporting member 16 to permit the repair of the switch mechanism 40 23 or the contacts 25. The thickness of the plate 29 and the length of the portion of the member 16 extending above the shoulder 28 are substantially the same so that the grooved face of the plate 29 will be flush with the edge of the member 16. The coil 31 is of less size than the 45 depth of the groove 30 so that the coil will lie below the grooved face of the plate 29.

The heater 16, 29 may be readily converted into an article support by a cover plate 33 having the peripheral portion arranged with a depending flange having a curled or beaded edge, as 50 shown at 34 in Figure 4. The diameter of the plate 33 is such as to have the flange slidingly engage the outer surface of the portion of the member 16 above the shoulder 28, as clearly 55 shown in Figure 2. When it is desirable to use the heater as an article support, the heating element 29, 31 is removed from the member 16 before placing the cover plate 33 on the member 16 to avoid the placing of the heating element in 60 circuit with the source of electricity by an accidental actuation of the switch 23.

The heater 16, 29 will be mounted centrally of the vertical axis of the pedestal 5 and therefore, there will be no possibility of tilting over the pedestal by placing a cooking utensil on the heater plate 29.

The lamps of the type illustrated in the drawing are usually positioned adjacent a chair and 70 the location of the switch 23 in the member 16

will permit the person seated in the chair to readily control the connecting and disconnecting of the heating element 31 with a source of electricity.

The switch 23 may be arranged as a four way 5 switch to control the circuit of both the lamp socket 7 and the heating element 31, so that the lamp socket may be placed in circuit when the heating element is out of circuit, the heating element may be placed in circuit when the lamp 10 socket is out of circuit, and both the lamp socket and heating element may be simultaneously placed in or out of circuit.

It should be understood that the heating element shown and described hereinbefore may be 15 used with any lamp socket supporting pedestal having the general characteristics of the lamp and pedestal shown in the accompanying drawing and that the invention is not restricted to the particular lamp pedestal illustrated in said 20 drawing.

Having thus described my invention, I claim:

1. In a combined illuminating and cooking means, a pedestal of tubular form in cross section having straight end portions and an offset 25 portion intermediate the end portions, one end portion being arranged with a supporting base at the free end, a tubular extension projecting from the end portion arranged with the supporting base, an electric lamp socket supported on 30 the end portion of the pedestal opposite the end portion arranged with the base and having electric conductors extending through the straight and offset portions of the pedestal, a dish shaped member mounted on the tubular extension to 35 extend into the space formed by the offset portion, and an electric heating element supported by the dish shaped member and having electric conductors extending through the tubular extension and connected to the conductors of the 40 lamp socket.

2. In a combined illuminating and cooking means as claimed in claim 1, a manually operative electric switch mounted in the dish shaped member and connected to the electric conductors of the heating element. 45

3. In a combined illuminating and cooking means, a pedestal of tubular form in cross section having a supporting base at one end and a tubular extension intermediate the ends, an 50 electric lamp socket supported on the end of the pedestal opposite the base, a dish shaped member having an annular shoulder at the open end and electric contact members mounted adjacent said shoulder and said dish shaped member 55 being mounted at the closed end on the extension of the pedestal, and an electric heating element having contact members on a face thereof and adapted to be mounted on the shoulder of the dish shaped member with the contact 60 members of the heating element in engagement with the electric contact members of the dish shaped member.

4. In a combined illuminating and cooking means as claimed in claim 3, a manually actuated electric switch mounted in the dish shaped member and connected in circuit with the contact members mounted in the dish shaped member. 65
